POST BINDER

Frank Stanley Schade, Holyoke, Mass., assignor to
 National Blank Book Company, Holyoke, Mass.,
 a corporation of Massachusetts

Application April 4, 1942, Serial No. 437,612

4 Claims. (Cl. 129—12)

This invention relates to an improvement in loose leaf binders known as post binders. My object is to improve the construction of this type of binder. Pertinent prior art structure is indicated in the Schade Patent No. 2,211,517 of 1940.

The general idea of my new construction is to lower the cost without lowering the efficiency, but in some respects improving it, as compared to prior art structure. According to my disclosure, the cost is lowered, for example by making my structure with a substantial proportion of wooden rather than metal parts. The efficiency of the new binder depends on the arrangement of the parts according to the plan which I will disclose.

In the drawing—

Fig. 1 shows a side elevation of the back and top units of the binder, with parts of the cover portions cut away;

Fig. 2 shows a longitudinal section through the top unit of Fig. 1 taken on line 2—2 of Fig. 1;

Fig. 3 is a plan view of the top unit of Fig. 1;

Fig. 4 is a detail view of parts which appear in small scale in Fig. 2 and are indicated in the top view of Fig. 3;

Fig. 5 is a side view showing a slightly modified construction. It is similar to that of Fig. 1 except the assembly gives a different hinge construction in the combination;

Fig. 6 is a view on line 6—6 of Fig. 5; and

Fig. 7 is a view of detail.

In making the structure illustrated, I had in mind today's scarcity of metal. It being both expensive and hard to get, I aimed at a new construction suitable for a substantial change from metal to wood material. The change of material might be also from metal to plastic, for example. In either case the new form and arrangement would give advantages. This will appear when the following detailed disclosure is fully considered.

The construction of Fig. 1 includes a top cover portion 2. It has a hinged binding strip 3. The flexible cloth hinge 4 itself is conveniently integral with the cloth covering material of stiffened portions 2 and 3. Such a top cover unit can be made on automatic machinery. It is a low cost and convenient part. A similar part is shown in the bottom unit. References 2', 3', and 4' correspond to described portions 2, 3, and 4.

On the outside of strips 3 and 3' I provide bars 5 and 5' of wood, plastic, or other non-metallic material. Wood is preferred. Bar 5 has two spaced recesses 6 on the top side (see Figs. 2 and 3). They are for pocketing and holding an automatic mechanism used to fasten the removable

cover unit to the binder posts 7, which posts are suitably attached to the bar 5' and strip 3'.

The automatic mechanism *a* is shown in Fig. 4. The mechanism per se is similar to that shown in said prior Patent No. 2,211,517, being there shown in Fig. 6. So it will be described herein briefly. The finger piece 9 is pressed upwardly by a V-shaped spring plate 9'. These pieces 9 and 9' are of about equal width. The lower portion of plate 9' rests on a saddle guard 9'', with an outer end projection resting in a fitting recess in material of piece 5, see Fig. 2. The upper and vertical part of the guard 9'' has a projection 50 at each corner, which projections engage notches 15 in the sides of piece 9. The latter is bent substantially as shown in Fig. 4. The part to the left of prongs 50 slopes downwardly. It is provided with a hole to pass a binder post when in one position, but cramp the post from passing in the position 20 of Fig. 2. Fig. 4 shows the normal position of the parts, as does Fig. 2. The operation is to press finger piece 9 downwardly at the right. This raises the left upwardly. The post hole moves toward the horizontal. This releases the 25 post from the binding position of Fig. 2. Except for the finger pressure on piece 9, the spring plate 9' holds the mechanism in cramping relation to the post. The pivot line of piece 9 is on top of piece 9'' between prongs 50, one on each top 30 corner. By itself, this mechanism is old, as indicated in the aforesaid Schade patent.

As indicated in Figs. 2 and 4, I provide metal staples 8. They serve to fasten bar 5 to strip 3. They also serve to retain the automatic mechanism *a* in recess 6. There are shown two posts 7, two recesses 6, two mechanisms *a*, and two staples 8. These are similar in their function so that the description of one will be enough.

Fig. 3 indicates how the staple 8 straddles latch 40 plate 9. As in Fig. 2, the staple prongs pass through the wooden bar 5, through the binder strip 3, and are bent over and tightly against the under side of strip 3. The latter may be made with an interior stiffening portion of cardboard. 45 The staple makes a good clinch against the covering cloth and cardboard material of strip 3. Such cloth material is not separately shown, to avoid too many lines in the drawing. The staple and its arrangement thus not only hold bar 5 and strip 3 together, but effectively retain latch plate 9 and its associated mechanism in place to operate in the recess of the bar. They all make a 50 most convenient arrangement for original putting together and later for taking apart for replacement and repair. The staple also acts as a ful-

crum stop for pivotal movement of latch plate 9. In this respect it cooperates with the latch plate 9 in the functioning of the latter. It is located to straddle plate 9 in the line of its notches 12. It will be seen that the simple staple serves many purposes.

In the modification shown in Figs. 5 and 6 a different hinge construction is indicated for the combination. In this embodiment the wooden bars 10 and 11, formed as are bars 5 and 5', serve as binding strips. Each bar is fastened to its adjacent cover portion by hinges 14.

The hinges, as shown, provide a stop for the inward swinging of the strips about the covers, although any suitable type of hinge may be employed for the purpose.

In Fig. 6 I have shown the hinge for the top cover in plan view to indicate the additional functions of these upper hinges. It will be understood that mechanisms *a* are located in recesses as described in the first embodiment. Here the staples 8' retain the mechanisms *a* by passing through the bar 10 and being bent against plate 15 of the hinge. Thus, the plate serves as a firm piece by which the staple may clinch the latch mechanism securely in the assembly. In addition, it will be noted that the plate 15 acts as a reinforcing piece for the post hole 16. Hence, the hinge increases the life of the binder by lessening the possibility of wear and tear in this construction.

It will also be noted that the hinges, being of thinner construction than the cardboard reinforced strips shown in Fig. 1, present a more compact binder.

Now that the two modifications have been disclosed I will point out more of the detail and advantages.

Referring to the form of Fig. 1, the bottom bar 5' is provided with a special bottom post section. It is shown as 17 in Fig. 7 where it appears much like an eyelet. The flange 18 is held on a shoulder by turned-over edge 19. The cover reinforced margin 3' is held by post section 20 screwing into 17 and with flange 21 to hold the cover section. This cloth hinge form of post binder is thus made with the bottom cover fastened to the bottom bar 5' by a special form of bottom post. It will be recalled, as described above, that the staple 8, among its other functions, fastened the top cover to the top bar 5. The construction gives a useful result.

Compared to prior constructions as made with metal bars or tubes for the posts and cloth hinges: I make the new construction at lower cost, involving less hand labor. Automatic machines are available to make cover elements having parts like 2, 4, and 3 of Fig. 1. But in making the old post binders with metal tubes instead of bars 5 and 5', it has been customary to wrap the cloth of the cover hinges around the stiff metal tubes. Thus, the part 3' would not be used. That is to say, the flattened metal tube has before seemed to be of particular advantage in serving as the stiffening portion and rendering such an element as my part 3' unnecessary. But in observing the subject as I have, it was no advantage. It required expensive hand operation in finishing the stiffening binding margin sections of the covers.

With my reconstruction it should be noticed that my cover sections are of a character such as can be made complete by automatic machines. Then the posts, the wooden bars, and mechanism carried by the bars are all quickly and inexpensively assembled. The bottom post sections

of Fig. 7 and the staples like 8 of Fig. 3 hold the things together in functional relationship. It will be seen particularly from Fig. 1 how well adapted the construction is for the renewal of either or both covers. The mechanism carried by bars 5 and 5' will customarily outlast a pair of covers 2 and 2'. By substituting a pair of new for old covers the book may be kept in fine condition as long as the mechanism lasts. The covers are relatively inexpensive.

The advantages over the prior constructions are exceedingly useful from the manufacturer's viewpoint. The nice appearance of the binder is retained. From the user's standpoint nothing is lost while the binder may now be lighter in weight. The user will find too that he can by easy repair or replacement operations keep his structure in perfect mechanical condition and with little expense in renewing covers keep an original good book appearance.

The observations in respect to the reasons for the new binder and comparisons with the older forms will show nicely coordinated results in many particulars. The new book structure involves much more than the substitution of other materials for metal, although that substitution is desirable, as mentioned in the beginning.

I claim:

1. A post binder having in combination a top cover unit provided with a solid bar of non-metallic material, wood for example, two recesses extending downwardly from the top face of said bar, one located adjacent each end of the bar, at each recess a staple with prongs passing through the bar adjacent the sides of the recess and with its prong-connecting portion lying across the recess from side to side at about the top level of the bar to provide a fulcrum line of operation of latching mechanism, an automatic spring-pressed post latching mechanism contained in the recess with a latch finger-operating piece presented at about the top of the recess with a downwardly slanting extension passing under said prong-connecting portion to provide a post-gripping piece at the opposite side of the portion, the transverse line of said extension as it passes under said prong-connecting portion forming a fulcrum line for pivotal movement of said finger-operating piece, said mechanism having spring means to maintain pressure of said parts on said fulcrum line, one of such latching mechanisms being assembled in each recess, post holes provided in the said bar and in the post gripping pieces of said mechanisms.

2. The structure of the claim 1 in combination with a back unit having a binding margin including a solid bar of non-metallic material, similar to the top unit, carrying the binding posts adapted to pass through the bar and latching mechanisms of the top unit.

3. A post binder having in combination a top cover unit provided with a solid bar of non-metallic material, wood for example, two recesses extending downwardly from the top face of said bar, one located adjacent each end of the bar, at each recess a cross piece of relatively very small cross-section spanning the recess from side to side at about the top level of the bar and firmly fastened to it, said cross piece adapted to function as a fulcrum line for latching mechanism, an automatic spring-pressed post latching mechanism contained in the recess with a latch finger-operating piece fulcrumed on said cross piece by spring pressure and with the finger-operating piece having a portion presented at about the

top of the recess with a downwardly slanting extension passing under and to the other side of said cross piece to provide a post gripping piece at such opposite side of the cross piece, one of such latching mechanisms being assembled in each recess, post holes provided in the said bar and in the post gripping pieces of said mechanisms.

4. The structure of claim 3 in combination with

5 a thin sheet metal hinge construction having one plate fastened on the side of the solid bar opposite from the side of its recesses and a post hole through such plate in alignment with the post hole in the post gripping pieces of the latching mechanism, one hinge being provided adjacent each recess.

FRANK STANLEY SCHADE.
